PREFABRICATED FLUE CONSTRUCTION

Russell O. Gunderson, Spokane, Wash., assignor
to Kaiser Aluminum & Chemical Corporation,
a corporation of Delaware

Application March 16, 1949, Serial No. 81,763.

10 Claims. (Cl. 263—46)

1

This invention relates to flues for use in industrial furnaces and more particularly to a prefabricated flue for use in carbon anode baking furnaces, wherein the furnace is divided into a plurality of carbon anode baking pits by means of the flues and wherein the baking pits are indirectly heated by the hot gaseous medium flowing through tortuous passages in the flues.

The prefabricated flue of the present invention is generally comprised of a base plate upon which the refractory bricks are suitably disposed so as to form a tortuous passage through the flue. Certain of these bricks have preformed holes which when brought into alignment form vertical shafts through the brickwork. Stud bolts are affixed to the base plate which threadedly engage removable tie rods and couplings inserted through the shafts in the bricks. These tie rods also serve to clamp a strongback to the top of the flue so that when the strongback and brickwork are clamped together the flue may be easily moved from one location to another.

Although the prefabricated flue of the present invention is adaptable for use in other types of industrial furnaces such as furnaces for calcining carbon cathode blocks, coke and coal and those for drying materials employed in aluminum reduction operations, it is particularly adapted for use in carbon anode baking furnaces. These furnaces are generally comprised of several sections that are intermittently exposed to heat. Each section in turn consists of several pits separated by refractory brickwork flues. Heat is indirectly transmitted to the various pits by means of a heated gaseous medium which travels through the passages in the flues so that as the refractories of the flue become heated, they in turn transmit heat to the pits. After the firing cycle is completed the pits in an individual section of the furnace are cooled by circulating air through the flues.

In the past whenever a flue needed replacement, it was broken out and an entirely new flue built up by masons working within the pits. The firing schedule of the furnace had to be accurately timed to allow for such maintenance work which in turn resulted in lost production time.

By the use of a prefabricated flue lost production time has been reduced to a minimum, since the entire flue can be prefabricated at some other part of the plant and transported directly to the place where the damaged flue is located. The damaged flue can then be completely removed and a new flue lowered into position.

In addition the use of prefabricated flues also makes possible more efficient use of the masons' time in building the flue, in that it enables them to use suitable jigs and fixtures in the construction thereof at a central location in the plant, which would otherwise be impossible to utilize be-

cause of the close working quarters within the pits.

Furthermore, the use of a prefabricated flue which can be transported to wherever it is needed eliminates the necessity of stockpiling materials near the furnaces thereby providing far less interference with operations within the plant. The use of such a flue also eliminates the safety hazard of working in a restricted pit with loose bricks handled by hand from above as well as the health hazard of working for extended periods in the extreme heat and dust filled air of the pits.

Accordingly it is an object of this invention to provide a prefabricated flue which can be easily assembled and moved into position within a furnace with a minimum loss of time and effort.

It is a further object of this invention to provide a flue which can be prefabricated at a central location within the plant by means of jigs and fixtures and then transported to the place where it is needed.

Another object of this invention is to provide a prefabricated flue which can be constructed with a minimum amount of parts.

A still further object of this invention is to provide a prefabricated flue, which when used will decrease the safety and health hazards for maintenance workmen in the plants which utilize such flues in their furnaces.

Another object of this invention is to provide a prefabricated flue, which when used will increase the operational efficiency of an industrial furnace.

Other objects, purposes and advantages of the invention will hereinafter more fully appear or will be understood from the following description of certain embodiments thereof during which reference will be made to the accompanying drawings wherein:

Figure 1 is a diagrammatic top plan view of a carbon anode baking furnace section, showing the location of the flues within the furnace and the path of flow of the gaseous medium therethrough;

Figure 2 is an elevational, longitudinal, sectional view of the prefabricated flue of the present invention;

Figure 3 is a plan view of the strongback shown in Figure 2;

Figure 4 is a plan view partially in section of the cap mounted on top of the flue;

Figure 5 is a sectional elevational view of one of the paving hole formers taken along line 5—5 of Figure 6;

Figure 6 is a plan view of the paving hole former shown in section in Figure 5;

Figure 7 is an enlarged view taken along lines 7—7 of Figure 2, with the coupling, which threadedly engages the base plate studs, removed.

With further reference to the drawings and

particularly Figure 1, it will be apparent that a plurality of prefabricated flues 10, the subject matter of the present invention are located in rows within a carbon anode baking furnace in such a manner as to serve as side partitions or walls for the various carbon anode baking pits 11 thereby formed therein. Headwalls 12 of the furnace can also be prefabricated in the manner of the flues 10. However, the invention will be described as applied to flues 10.

In laying up the brickwork for the flues of the furnace the bricks are bonded together and so constructed and arranged, in a manner well known in the art, as to provide tortuous passages through which a heated gaseous medium passes as is disclosed by arrows showing the direction of flow in Figures 1 and 2. This heated gaseous medium in turn heats the refractories of the flues and thereby indirectly heats the carbon anodes in the baking pits.

The prefabricated flue embodied in the present invention is comprised of a base plate 13, upon which a channeled member 14, is mounted with its channeled portion facing downwardly. A plurality of stud bolts 15 whose upper portions are threaded are then inserted through holes in the channeled member and are either welded to or threadedly engage a bore in the base plate. A nut 16 may also be welded to the base plate and the stud bolt passed therethrough to lock the stud bolt more securely in position and prevent it from being withdrawn through the hole in the channeled member 14.

The flue is then built up by laying a plurality of brick courses upon the base plate until the proper height for the flue is attained. During this operation the bricks are so layed up that tortuous passageways are provided in the flue, such a conventional passageway being shown in Figure 2, wherein the baffle 17 and openings 18 in the side are constructed by the brick masons in a manner well known in the art.

The tortuous passage arrangement in the flue may be modified as desired by merely rearranging the baffles. Any refractory suitable for the conditions within the furnace may be employed in the flue. Conventional firebrick has been found to be quite satisfactory. It has also been found advantageous to use insulated refractories at the upper portion 19 and lower portion 20 of the flue.

In laying up the bricks provision is made whereby the bricks at each of the ends of the flues are so arranged that preformed holes in certain of the bricks in the several courses will be brought into vertical alignment so that two shafts 27 are provided into which tie rods 21 may be inserted.

Permanently affixed to the lower end of the tie rods 21 are couplings or cylindrical sleeves 22. These sleeves have internal threads at the lower portion thereof so that they may slip over and upon turning threadedly engage the stud bolts 15. These sleeves are also either welded to or threadedly engage the lower extremity of the rods 21.

Before the tie rods 21 and couplings are inserted within the shafts 27, a top frame or cap 23 best shown in Fig. 4, comprised of side and end channel irons 24 and 25 which are welded together and also tied together by means of a plurality of steel rods 26, is placed upon the top of the flue as shown in Figure 2.

After this top frame is placed on top of the flue and affixed thereto by suitable means, concrete may be poured into the frame whereby the

frame is permanently cemented to the top of the flue. Thus, a reinforced concrete top will be provided having permanent steel sides which will not chip off or become dislodged during normal mechanical operations and abuse.

During the cement pouring operations paving hole formers 28 with handles or bails 29 are inserted within the top frame and above the upper extremities of shafts 27 and then removed once the concrete becomes hardened. The use of these formers provides a means for forming an opening 33 in the concrete which will be in alignment with each shaft 27, as well as a means for preventing the concrete while soft and plastic from flowing into the said shafts.

Bearing plates 30 with holes 32 may be affixed to the cap 23 if desired. If the cap is cement filled as shown in Fig. 2, they are inserted within the cement before it sets at each extremity of the top frame. These plates then serve as bearing members for the strongback 31 at that point on the flue top where the strongback rests upon the concrete adjacent the shafts 27 to prevent chipping of the concrete at this point because of the weight of the strongback, and the wear on the hole 33 caused by the tie rods. Holes 32 are also in alignment with shafts 27 and the openings 33 formed by the paving hole former 28. When plates 30 are used with a cement filled cap they are first put upon the cement and the paving hole formers thrust through the holes 32 therein, directly above shafts 27.

The strongback 31 is placed upon the top frame 23 in such a manner that it overlaps the frame, and as best shown in Fig. 3 as comprised of two upright channel irons 34 whose channels face outwardly. These channels are closed by steel side strips 35, welded to said irons. The ends of the channel irons are also covered by steel end strips 36.

It will be noted by referring to Fig. 3 that the channel irons 34 are not placed in exact back to back relationship but are spaced apart to provide a longitudinal slot or opening 37 into which a handle or bail 38 may be inserted.

The channel irons 34 are welded together at a plurality of points by means of bars generally indicated at 39, and the strongback bail after insertion in slot 37 is also welded or retained in place by any suitable means.

On the upper surface of each extremity of the strongback a second bearing plate 40 is positioned. Each of these plates has an aperture 41 which is in alignment with hole 32, opening 33 and shaft 27. The tie rods and couplings can be permanently affixed to the strongback by means of the nuts and washers 42 and 43, respectively.

When tie rods 21 with their associated couplings are inserted through the various holes or openings in the bearing plates, strongback, concrete cap and bricks and threadedly engage the stud bolts 15 on the base plate, and when nuts 42 with washers 43 are tightened about the upper threaded extremity of each tie rod, the strongback and flue are clamped together. Thus, it is obvious that by this method the flue will be securely held together during the time it is moved into the furnace by the building crane. After the flue has been placed in the desired spot, the tie rods and couplings are removed as well as the strongback, all of which can then be used again on the next flue to be moved.

When the tie rods have been removed from a flue which has been placed in position within the furnace, the shafts 27 may advantageously be

used in taking temperature measurements and in making flame observations.

In addition after the flue has been placed in position and the strongback and tie rods have been removed, the use of a concrete, steel reinforced flue top will provide a firmer, safer footing for the men working on the furnace, and the life of the flue is increased in that the reinforced concrete top acts as a beam across its entire length, thereby uniformly distributing any heavy loads such as buckets, carbon baskets and jib cranes, which previously were concentrated loads upon the flues.

While the invention has been shown in but one form, it will be obvious to those skilled in the art that it is not so restricted, but is susceptible of various changes and modifications, without departing from the spirit thereof and all within the scope of the appended claims wherein:

What is claimed is:

1. A prefabricated flue assembly of the type described, which is adapted to be transported to and inserted as a unit in a carbon anode baking furnace and the like, comprising a base plate, a plurality of spaced refractory side walls mounted upon and extending upwardly from said base plate, a plurality of coupling members affixed to and projecting upwardly from said base plate, cross-tie refractory members interposed between and attachable to said refractory side walls at predetermined points thereon so as to provide a top, apertured end walls and interior baffle means for said flue assembly, said top being further provided with vertical openings in substantial registry with said coupling members on said base plate and removable means attachable to a hoisting apparatus for transporting said flue assembly as a unit from one location to another, said means including a strongback member positioned on the top of said flue assembly having tie rods dependently attached thereto, said tie rods being adapted to be inserted in the openings in the top of said flue assembly and to be removably fastened to the coupling members on said base plate, when said strongback member is placed upon the top of said flue assembly.

2. A prefabricated flue assembly of the type described which is adapted to be transported as a unit to and inserted in a carbon anode baking furnace and the like, comprising a base plate, a plurality of spaced refractory side walls mounted upon and extending upwardly from said base plate, cross-tie refractory members interposed between and attachable to said refractory side walls at predetermined points thereon and providing a top, apertured end walls and interior baffle means for said flue assembly, a plurality of coupling members affixed to and projecting upwardly from said base plate, and removable means attachable to a hoisting apparatus for transporting said flue assembly as a unit from one location to another said means including a strongback member positioned on the top of said flue assembly having tie rods dependently attached thereto, said tie rods being adapted to be removably secured to the coupling members on said base plate, when said strongback member is placed upon said flue assembly.

3. A prefabricated flue assembly of the type described which is adapted to be transported to and inserted as a unit in a carbon anode baking furnace and the like, comprising a base plate, a plurality of spaced refractory side walls mounted upon and extending upwardly from said base

plate, a plurality of stud bolts affixed to and projecting upwardly from said base plate intermediate said refractory side walls, cross-tie refractory members interposed between and attachable to said refractory side walls at predetermined points thereon so as to provide a top, apertured end walls, and interior baffle means for said flue assembly, said top being further provided with vertical openings in substantial alignment with said stud bolts on said base plate and removable means attachable to a hoisting apparatus for transporting said flue assembly as a unit from one location to another, said means including a strongback member positioned on the top of said flue assembly and having tie rods dependently attached thereto, said tie rods being adapted to be inserted in the openings in the top of said flue assembly and removably fastened to the stud bolts on said base plate, when said strongback member is placed upon the top of said flue assembly:

4. A prefabricated flue assembly of the type described which is adapted to be transported to and inserted as a unit in a carbon anode baking furnace and the like, comprising a base plate, a plurality of spaced refractory side walls mounted upon and extending upwardly from said base plate, a plurality of coupling members affixed to and projecting upwardly from said base plate, cross-tie refractory members interposed between and attachable to said refractory side walls at predetermined points thereon so as to provide a top, apertured end walls, and interior baffle means for said flue assembly, a metallic frame reinforcing cap mounted upon and secured to the top of said flue assembly, said flue assembly top also being provided with vertical openings in substantial alignment with said coupling members on said base plate, and removable means attachable to a hoisting apparatus for transporting said flue assembly as a unit from one location to another, said means including a strongback member positioned on the top of said flue assembly and having tie rods dependently attached thereto, said tie rods being adapted to be inserted in the openings in the top of the flue assembly and removably fastened to the coupling members on said base plate, when said strongback member is placed upon the top of the flue assembly.

5. A prefabricated flue assembly of the type defined in claim 4 wherein the reinforcing cap for the top of the flue assembly is substantially filled with cement.

6. In a carbon anode baking furnace consisting of a plurality of flues having baffle means therein so arranged as to provide a tortuous passage for hot gases flowing therethrough, the improvement which comprises a prefabricated flue assembly which is adapted to be transported to and inserted as a unit in the said furnace, said flue assembly including a base plate, a plurality of spaced refractory side walls mounted upon and extending upwardly from said base plate, a plurality of coupling members affixed to and projecting upwardly from said base plate, cross-tie refractory members interposed between and attachable to said refractory side walls at predetermined points thereon so as to provide a top, apertured end walls and interior baffle means for said flue assembly, said flue assembly top also being provided with vertical openings in substantial alignment with said coupling members on said base plate, and removable means attachable to a hoisting apparatus for transporting said flue assembly as a unit from one location to another,

said means including a strongback member positioned on the top of said flue assembly having tie rods dependingly attached thereto, said tie rods being adapted to be inserted in the openings in the top of said flue assembly and removably fastened to the coupling members on said base plate when said strongback member is placed upon the top of said flue assembly.

7. In a carbon anode baking furnace consisting of a plurality of flues having baffle means therein so arranged as to provide a tortuous passage for hot gases flowing therethrough, the improvement which comprises a prefabricated flue assembly adapted to be transported as a unit to and inserted in said furnace, said flue assembly including a base plate, a plurality of spaced refractory side walls mounted upon and extending upwardly from said base plate, a plurality of stud bolts affixed to and projecting upwardly from said base plate, cross-tie refractory members interposed between and attachable to said refractory side walls at predetermined points thereon so as to provide a top, apertured end walls and interior baffle means for said flue assembly, a metallic frame reinforcing cap for the top of said flue assembly, and said flue assembly top being further provided with vertical openings in substantial alignment with said stud bolts on said base plate and removable means attachable to a hoisting apparatus for transporting said flue assembly as a unit from one location to another, said means including a strongback member positioned on the top of said flue assembly having tie rods dependingly attached thereto, said tie rods being adapted to be inserted in the openings in the top of the flue assembly and removably fastened to the coupling members on said base plate when said strongback member is placed upon the top of said flue assembly.

8. In a carbon anode baking furnace consisting of a plurality of flues having a baffle means therein so arranged as to provide a tortuous passage for hot gases flowing therethrough, the improvement which comprises a prefabricated flue assembly adapted to be transported as a unit to and inserted in said furnace, said flue assembly including a base plate, a plurality of spaced refractory side walls mounted upon and extending upwardly from said base plate, a plurality of stud bolts affixed to and projecting upwardly from said base plate, cross-tie refractory members interposed between and attachable to said refractory side walls at predetermined points thereon, so as to provide a top, apertured end walls and interior baffle means for said flue assembly, a metallic frame reinforcing cap adapted to be filled with cement mounted upon the top of said flue assembly and said flue assembly top and said cement filled cap being further provided with aligned vertical openings in substantial registry with said stud bolts on said base plate, and removable means attachable to a hoisting apparatus for transporting said flue assembly as a unit from one location to another, said means including a strongback member positioned on the top of said flue assembly and having tie rods dependingly attached thereto, said tie rods being adapted to be inserted in the openings in the top and cap of said flue assembly and removably fastened to the stud bolts on said base plate when said strongback member is placed upon the top of said flue assembly.

9. A prefabricated flue assembly of the type

described which is adapted to be transported to and inserted as a unit in a carbon anode baking furnace and the like, comprising a base plate, a plurality of spaced refractory side walls mounted upon and extending upwardly from said base plate, a plurality of coupling members affixed to and projecting upwardly from said base plate, cross-tie refractory members interposed between and attachable to said refractory side walls at predetermined points thereon and providing a top, apertured end walls and interior baffle means for said flue assembly, said top being further provided with vertical openings in substantial alignment with said coupling members on said base plate and removable means readily attachable to a hoisting apparatus for transporting said flue assembly as a unit from one place to another, said means including a strongback member positioned upon the top of said flue assembly, said strongback member being comprised of a plurality of elongated and oppositely disposed channel members fastened together by a plurality of spacing bars and said strongback member also having a plurality of tie rods dependingly attached thereto, said tie rods being adapted to be removably inserted in the openings in the top of said flue assembly and removably fastened to the coupling members on said base plate, when said strongback member is placed upon the top of said flue assembly.

10. A prefabricated flue assembly of the type described, which is adapted to be transported to and inserted as a unit in a carbon anode baking furnace and the like, comprising a base plate, a plurality of spaced refractory side walls mounted upon and extending upwardly from said base plate, a plurality of stud bolts affixed to and projecting upwardly from said base plate, cross-tie refractory members interposed between and attachable to said refractory side walls at predetermined points thereon so as to provide a top, apertured end walls and interior baffle means for said flue assembly, a reinforcing metallic frame cap mounted upon the top of said flue assembly and said flue assembly top also being provided with vertical openings in substantial registry with said stud bolts on said base plate and removable means readily attachable to a hoisting apparatus for transporting said flue assembly as a unit from one place to another, said means including a strongback member positioned upon the cap of said flue assembly, said strongback member being comprised of a plurality of elongated and oppositely disposed channel members fastened together by a plurality of spacing bars and said strongback member also having tie rods dependingly attached thereto, said tie rods being adapted to be inserted in the openings in the top of said flue assembly and removably fastened to the stud bolts on said base plate when said strongback member is placed upon the cap of said flue assembly.
